CEMENTED SHOE

Charles Miller, Long Island City, N. Y.

Application November 27, 1933, Serial No. 699,868

10 Claims. (Cl. 36—76)

This invention relates to cemented shoes.

When shoes having straps as parts of the upper have been made under the cemented shoe processes of the prior art, considerable difficulty has been experienced in properly cementing the outsole at those portions where the said straps are lasted to the insole.

It is therefore an object of this invention to devise a method, of making cemented shoes having straps as a part of the upper thereof, in which the outsole is uniformly cemented to the shoe.

Also, it is an object of this invention to improve the shank structure of a shoe having a metallic shank stiffener, particularly with regard to the attachment of the outsole at this portion.

And it is a further object of this invention to prepare an outsole for use in a cemented shoe so that the same may be firmly attached to the shoe, and permit of a finished product having all the outward appearances of a turned shoe.

It is another object of this invention to improve the mounting of the shank stiffener in a cemented shoe.

Finally, it is an object of this invention generally to improve the cemented shoe art and to produce cemented shoes which are durable, and stylish and which have all the desirable characteristics of turned shoes.

These and other objects of the invention will be readily apparent to those skilled in the art from the following description taken in conjunction with the accompanying drawing in which:

Fig. 1 is a perspective view of a shoe partially completed, the outsole being omitted.

Fig. 2 is a perspective view of an outsole prepared for attachment to the shoe shown in Fig. 1.

Fig. 3 is a sectional view taken along the line 3—3 of Fig. 1.

Fig. 4 is a sectional view taken along the line 4—4 of Fig. 2.

Fig. 5 is a detail view of a shank stiffener having a covering.

The present invention is disclosed specifically as applied to a so-called Sbicca method shoe, such as is disclosed in U. S. Letters Patent 1,838,708 issued to Frank Sbicca and U. S. Letters Patent 1,902,725 issued to the same inventor. However, it must be strictly understood that the present invention is not so limited and that the same may also be applied to any cemented shoe in which separate insole and outsole members or their equivalents are used.

Referring in detail to the drawing the shoe 10 having an upper 11 provided with strap members 12 forming a part of the vamp, and strap members 13 forming a part of the quarters and counter section, is lasted to the insole 14, which has previously been mounted upon the last 15 shown in dotted lines in Fig. 1. This insole 14 is pro-

vided with a rand 14a forming the forward portion, a shank portion 14b and a heel portion 14c. Mounted upon the shank portion 14b by tacks 16 is a shank stiffener 17 having an arcuate section 18 running lengthwise thereof. A fabric sheath 19 or covering surrounds the stiffener 17. Pre-formed wedge shaped strips of leather 20 are cemented to the shank portion with one edge abutting the stiffener. The strips 20 abut against the stiffener and extend from a point adjacent to the heel breast down to the end of the stiffener. The thin edge of the strips runs a little inside of the side edges of the shank portion as shown in Figs. 1 and 4. These strips together with the stiffener 17 and its sheath 19 form a substantially convex surface on the shank portion of the insole. The sheath, after it is mounted upon the stiffener is saturated with a cement having a cellulose nitrate base and which readily becomes tacky upon the application of a suitable solvent.

Referring now to Fig. 1, it will be seen that the spaces between the straps 12 are free of the upper of the shoe. Consequently when the outsole is attached, it must be cemented to the insole member 14a at the intermediate points, but the edges of the straps which come in contact with the sole will keep the same out of contact with the insole member 14a at the said intermediate parts. This not only results in an unsightly shoe, but the same is substantially weaker due to the incomplete cementing of the outsole. To overcome this defect, small leather wedges, 22 substantially triangular in shape are inserted between the edge of the last and the rand 14a, (Fig. 1). These wedges 22 are just wide enough to fit in between the straps 12 and are as thick as the straps 12. Now, when the outsole is placed on the shoe, and pressure is applied to cement the same in place, the leather wedges 22 bring the rand 14a into contact with the outsole, and permit these portions to be cemented to the outsole. Of course, for different styles of the upper the space between the straps will vary, and the wedges 22 are prepared to fit the particular shoe in which they are to be used. Upon completion of the shoe, and withdrawal of the last, the wedges fall out, and may either be used again or thrown away.

The heel seat 40 is filled with a composition of sawdust and cement. The filling is leveled off flush with the inturned edges of the upper in the heel seat lasting. This cement is of the above mentioned type and hardens to form a firm foundation for the mounting of the heel.

The shoe is now ready for the application of the outsole which is first prepared as follows:

The properly shaped outsole member 30, having a raised ball section 31 as described in the aforementioned Sbicca patents, is grooved at 32 to receive the shank stiffener 17 mounted on the insole, and to embrace the same firmly when the

outsole is pressed onto the shoe. Along the edge of the shank portion of the outsole on both sides thereof there are provided bevelled edges 33, concave in cross action and extending substantially from the ball line to the heel breast. The edge of this bevel is colored the same as the upper of the shoe to which it is to be applied. The sole is now coated over those portions which are to contact with the lasted edge of the upper, the edge of the rand, and the shank portion of the insole with a cement such as is now commonly used in cemented shoes, and the cement is allowed to dry.

Before the sole is layed, the cemented surface is made tacky, following which the sole is put in place upon the shoe, and pressure is applied to fix the same properly in position.

The pressure applied to the outsole brings the same firmly into contact with the lasted edge of the upper as well as the edge of the rand 14b and where the upper is cut away, between the straps, the insole is cemented to the outsole, due to the use of the wedges 22. Also, the shank portion of the outsole is pressed onto the convex surface formed by the shank stiffener 17 and the strips 20, with the crown of this surface fitting into the groove 32. The adhesive forms a solid union, and the sheath 19 sticks to the groove. With the outsole in place the shank portion of the outer sole is pressed into a substantially convex surface, and the edges of this section taper down and merge into the edge of the shank portion of the insole. This insures a well defined narrow edge at the shank, which is a highly desirable characteristic of a well made shoe. This effect is further emphasized by the fact that the edge of the outsole is colored to match the upper thus detracting from the apparent thickness of the outsole of the shank. It will be understood that the degree of curvature of the convex surface on the shank portion of the outsole is less than that of the surface to which it is attached, due in the main, to the groove 32.

After the sole is layed, the heel is attached, and the finishing operations are performed in the usual manner.

It will be understood that many changes in the herein disclosed specific embodiment of this invention will suggest themselves to those skilled in the art, which changes are not a departure from the spirit and scope of this invention. I therefore do not intend to be limited in the scope of this invention except as defined in the appended claims.

Having thus described my invention I claim:

1. In a shoe, an insole having forward, shank, and heel sections, a shank stiffener mounted upon said shank section, pre-formed wedge members comprising strips of sheet material mounted upon said shank section in abutting relation to said stiffener and extending longitudinally of the latter, and an outsole attached to said insole.

2. In a shoe, an insole having forward, shank, and heel sections, a shank stiffener mounted upon said shank section, individual wedge members comprising strips of sheet material mounted upon said shank section in abutting relations to said stiffener, and extending from said heel section to said forward section.

3. In a shoe, an insole having forward, shank, and heel sections, a shank stiffener mounted upon said shank section, pre-formed wedge members comprising strips of sheet material mount-

ed upon said shank section in abutting relation to said stiffener, said wedge members extending longitudinally of the stiffener and forming with the stiffener a substantially convex surface at the shank section of the shoe, and an outsole 5 attached to said insole.

4. In a shoe, an insole having forward, shank, and heel sections, a shank stiffener mounted upon said shank section, said stiffener being provided with a sheath, pre-formed wedge members 10 mounted on said shank section adjacent said stiffener, said wedge members comprising strips of sheet material extending longitudinally of the stiffener and forming with the stiffener a substantially convex surface at the shank section 15 of the shoe, and an outsole cemented to said insole to the sheath of shank stiffener and to said strips of sheet material.

5. In a shoe, an insole having forward, shank and heel sections, a shank stiffener mounted upon 20 said shank section, pre-formed wedge members comprising strips of sheet material mounted upon said shank section in abutting relation to said stiffener, and an outsole attached to said insole, said outsole being provided with a groove to 25 receive said stiffener.

6. In a shoe, an insole having forward, shank and heel sections, a shank stiffener mounted upon said shank section, pre-formed wedge members comprising strips of sheet material mounted upon 30 said shank section in abutting relation to said stiffener, and an outsole attached to said insole, said outsole having a shank section the side edges of which have a concave bevel.

7. In a shoe, an insole having forward, shank 35 and heel sections, a shank stiffener mounted upon said shank section, pre-formed wedge members comprising strips of sheet material mounted upon said shank section in abutting relation to said stiffener, and an outsole attached to said 40 insole, said outsole having a shank section the side edges of which have a concave bevel, colored to match the upper of the shoe.

8. In a shoe, an insole having forward, shank, and heel sections, a shank stiffener mounted 45 upon said shank section and extending above the surface thereof, an outsole overlying said stiffener and spaced thereby from the surface of said insole shank section, and pre-formed means comprising strips of sheet material located in and substantially filling the space between said outsole and said insole shank section, said outsole being cemented to said strips.

9. In a shoe having an upper, an insole member having a shank section, a shank stiffener 55 mounted upon said shank section, an outsole overlying said stiffener and spaced thereby from the surface of said insole shank section, and strips of leather extending longitudinally of said shank section between the latter and said outsole 60 on opposite sides of said shank stiffener.

10. In a shoe having an upper, an insole member having a shank section, a shank stiffener mounted upon said shank section, an outsole 65 overlying said stiffener and spaced thereby from the surface of said insole shank section, and wedge members comprising strips of leather extending longitudinally of said shank section between the latter and said outsole on opposite sides of said shank stiffener, said outsole being cemented to said strips.

CHARLES MILLER.
